UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,298,568.

Specification of Letters Patent. Patented Mar. 25, 1919.

Application filed October 30, 1914. Serial No. 869,468.

To all whom it may concern:

Be it known that I, CHARLES F. Root, a citizen of the United States of America, residing at Ravenna, in the county of Portage and State of Ohio, have invented certain new and useful Improvements in Safety Devices, of which the following is a specification.

My invention relates to certain new and useful improvements in safety devices for staying machines and punching presses, though equally applicable to any character or type of a machine which has a reciprocating or oscillating work engaging element, 15 as, for example, a printing press.

The object of my invention is to provide means for automatically preventing the link that imparts movement to the reciprocating or oscillating work engaging element from 20 operating when an obstruction is inadvertently or otherwise placed between the element and the anvil or bed and upon engagement of the element with the obstruction.

It is well known in the operation of machines, that are provided with a reciprocating or oscillating work engaging element which exerts a pressure upon an anvil or bed, that there is great danger of the operator's fingers or hands being inadvertently placed between the anvil or bed and the reciprocating or oscillating element that exerts a pressure to perform the work with the result that the fingers or hands are 35 crushed or injured.

This is especially true when it is necessary for the operator of the machine to perform work that requires him to place his hands or fingers in close proximity to that 40 part of the anvil or bed upon which the work engaging element exerts a pressure to perform its work and in manipulating the work the operator's hands or fingers are liable to slip between the work engaging 45 element and the anvil or bed at the time the work engaging element is about to exert a pressure to perform its work thereby injuring the operator.

The primary object, therefore, of my invention is to provide means of releasing the pressure that is exerted by the reciprocating or oscillating element upon the anvil or bed to perform the work when an obstruction is interposed between the anvil or bed 55 and the reciprocating or oscillating element.

Further, the invention aims to provide means which is incorporated in the reciprocating or oscillating element so as to only render the latter operative or rigid (at a predetermined point) just prior to or at 60 the instant of the commencement of the punching, pressing, printing, joining or stamping operation, or, in other words, at the instant that the reciprocating or oscillating element is about to enter into actual 65 or physical contact with the work.

The invention further provides means which is sensitive to operation by the finger or hand of the operator, should the finger or hand be in a position subject to injury 70 by the reciprocating or oscillating element, without actual injury to the finger or hand.

Further, the invention aims to provide a structure which can be adjusted to operate in connection with material possessed of 75 varying thicknesses.

The objects above described are set forth in Letters Patent granted to me bearing date of March 9, 1915, Patent Number 1,131,161; pending application bearing Serial Number 80 857,016, filed Aug. 17, 1914; and pending application Serial No. 864,974, filed Oct. 5, 1914; and the present application has the same objects in view in a generic sense but includes specific improvements in the structure described in said application, and consists in the following new features:

A cam operated coupling member which is adapted to couple and uncouple a link mechanism to and from the crank pin, a 90 separable stationary cam plate for operating the coupling member that can be attached to and removed from the driving means of a reciprocating or oscillating element of a machine without changing or 95 altering the machine or driving means, and means for coupling the work engaging element to and positively preventing the crank pin of the driving means from exerting a pressure upon the work engaging element 100 until the crank pin has traveled to a predetermined point in its working stroke.

A further object is to so construct and arrange the parts comprising the means for coupling the crank pin of the driving means 105 to the work engaging element in such a manner that when the work engaging element is subjected to resistance or pressure before the work engaging element reaches a predetermined point in its working stroke, 110

that it will "idle" instantly because the crank pin of the driving means is permitted to complete its working stroke freely and independent of the coupling means and because there is no friction between the parts comprising the coupling means to be overcome or to be counteracted by the pressure or resistance.

A further object is to provide a safety device of a simple arrangement and of especial efficiency that is composed of few parts.

The invention in brief comprises the following instrumentalities: a stationary cam plate, a coupling member and a slotted link. I attain these and other objects by the mechanism illustrated in the accompanying drawing, in which:

Figure 1 is a front elevation of a conventional type of a staying machine showing my invention applied thereto and also showing the finger of the operator interposed between the anvil (which has a paper box mounted thereon) and the reciprocating work engaging element. In this view the coupling member is shown in uncoupled position as the work engaging element has been subjected to pressure by the finger before reaching the pre-determined pressure point of its working stroke.

Fig. 2 is a detail view, in front elevation, of the slotted link, coupling member, stationary cam plate, and auxiliary parts showing the coupling member in uncoupled position in full lines and in coupled position in dotted lines.

Fig. 3 is a side view partly in section showing the slotted link with the coupling member mounted thereon, and both assembled with the stationary cam plate, the end of which is loosely fitted over the periphery of the disk of the driving means.

Fig. 4 is a side elevation partly in section of Fig. 1 on a reduced scale.

Fig. 5 is a side elevation of the slotted end of the link showing a yielding friction mechanism applied thereto.

Fig. 6 is a plan view partly in section of Fig. 5.

In the drawings, the driving shaft 1 is provided with a disk 2 having a crank pin 3, the shaft being journaled in suitable bearings in the L shape arm 4 of a conventional type of a staying machine. Movement is imparted to the driving shaft 1 by the driving pulley 5. A head 6 reciprocates between the ways 7 and has a stud shaft 8 secured thereto. A follower or work-engaging element 9 is securely attached to the head 6 and co-operates with the usual anvil (or bed) 10 of a staying machine or the like.

For the purpose of connecting the stud shaft 8 of the head to the crank 3 of the driving shaft 1, by means of which a reciprocating movement is imparted to the head 6, a link 11 which is adapted to be coupled

with the crank pin 3 by the coupling member 12, is provided. The link 11 is cut away or reduced on one side thereof at 13 forming a shoulder 14. A circular depression 15 is formed in the side of the link that forms the shoulder 14 and the end 16 of the coupling member is pivotally fitted in said circular depression.

The circular depression 15 is formed contiguous with the cut away portion 13 and is located so as to provide a pocket for the end 16 of the coupling member, by means of which the coupling member is maintained in its proper place. A bushing 17 which is provided with an annular flange 18 is preferably mounted upon the crank pin. The link 11 is provided with an oblong slot 19.

In assembling, applying and constructing my safety device, a stationary cam plate 20 is provided having its upper end counter-bored at 21 to fit over the disk 2 and the other end is provided with a slot 22 to fit the periphery of the bushing 23 by means of which the stationary cam plate is held in place and provides a clearance space for the stud shaft 8 to travel in.

The crank pin 3 projects through the aperture 24 of the cam plate. The link 11 carrying the coupling member is loosely mounted upon the crank pin or the bushing 17 thereof, as shown in Fig. 2. The cam plate is provided with a cam 25 and a pin 26 is secured to the coupling member and is adapted to co-operate with the cam to actuate the coupling member. An aperture 27 is formed in one end of the link 11 to provide a bearing for the stud shaft 8 of the head 6. An annular flange 28 is provided on the bushing 23 for the purpose of keeping the stationary cam plate and link in juxtaposition to each other.

The operation of my device upon every revolution of the driving shaft, is as follows:

When movement is imparted to the driving shaft, the crank pin 3 imparts a combined oscillating and reciprocating movement to the link which carries the coupling member with it. When the crank pin which carries the link commences or is about to travel upon its down or working stroke, the throw of the link in one direction forces the cam pin 26 in contact with the point 29 of the cam 25 thereby actuating the coupling member and forcing it to rock to its uncoupled position, as shown in full lines in Fig. 2, the coupling member then remains in said uncoupled position during its working stroke until the pin 26 reaches and passes beyond the point 30 of the cam at which point the pin is released from the cam, permitting the coupling member to rock upon its pivot and to be forced to its coupled position which brings the end 31 of the coupling member directly underneath the crank pin 3 in a position to receive pressure from the

crank pin during the balance of the working stroke.

When the link reaches the end of its working stroke and starts its up or idle stroke, the throw of the link in the opposite or reverse direction carries the pin 26 through the clearance space 32, which is formed in the cam plate, until it again reaches the point 29 of the cam 25 at which time the above described operation again takes place. A coil spring 33 is attached to the link and coupling member 12 and normally exerts its tension to rock the coupling member and force it to its coupled position beneath the crank pin so that at the instant the cam pin 26 is released, the end 31 of the coupling member is forced beneath and coupled with the crank pin, as shown in dotted lines in Fig. 2.

In practice, I have found it convenient to arrange the cam so that it will permit the coupling member to couple the crank pin to the link for the purpose of exerting a pressure upon the work engaging element just prior to its acting on the work. It is apparent, however, that the crank pin can be coupled to the link for exerting a pressure upon the work engaging element at varying points in its working stroke by changing the dimensions of the cam.

The above describes the operation of my device when it is operating normally without any obstruction being projected or interposed between the work engaging element and its anvil or bed.

If an obstruction, as for instance the finger 34, is interposed or projected between the work engaging element 9 and the work on the anvil 10 (or bed) and the work engaging element contacts with said obstruction in making its working stroke before it reaches the predetermined point at which it is subjected to pressure for the purpose of acting upon the work, the head will be arrested and idle, and the crank pin will travel in the slot 19 freely and independent of the link or its mechanism as the cam pin will be in contact with the cam positively preventing the coupling member from being forced by the spring 33 to coupled position as shown by dotted lines in Fig. 2. The crank pin continues to travel freely in the slot 19 until the obstruction is removed permitting the head and link to drop by gravity, the link sliding in the slot 19 over the periphery of the crank pin until the cam pin passes the point 30 of the cam 25 at which point the pin enters the clearance space 32 permitting the coupling member to be again forced into coupled position as shown by dotted lines in Fig. 2.

My device is so constructed that the work engaging element is preferably not subjected to pressure to perform its work until it is in close proximity to or just about to contact with the work so that any object, such as a

finger or the like, that is interposed between the work engaging element and the work, will render the work engaging element inoperative to exert pressure upon the work or object.

A ball 35 is forced in contact with the bushing 17 by the spring 36 to provide a slight friction to yieldingly hold the link in a proper relative position for coupling the crank pin to the link.

Attention is called to the fact that the coupling member is held in uncoupled position by cam action until the work engaging element reaches a predetermined point in its working stroke, and that the stationary cam plate can be readily attached to the end of the driving shaft and held in place by the bushing 23 without altering the machine in any way and without the use of any appliance other than the device itself which is self contained.

It will further be noted that the parts cannot be improperly assembled as they must be mounted and held upon the bushing or crank pin in operative relation preparatory to connecting them to a staying machine or the like. The coupling member is prevented from rocking too far underneath the crank pin by the stop 37.

The combination, construction and arrangement of the parts as above described, provide a non-collapsible means for connecting the crank pin and work engaging element which permits the crank pin to exert a pressure upon the work engaging element at a predetermined point in its working stroke when its path is free and means to permit the crank pin to travel freely and independent of any mechanism when the work engaging element is subjected to pressure prior to its reaching said predetermined point in its working stroke.

What is claimed is:

1. In a safety device, in combination with a reciprocating work engaging element, a driving means, and means to connect the driving means and work engaging element including a stationary cam plate carried by the driving means and having a cam formed therein, a link, a coupling member movably connected to the link and normally tending to operative movement, and means on the coupling member to engage the cam to hold the member inoperative until the work-engaging element reaches a predetermined point in its working stroke.

2. In a safety device, in combination with a movable work engaging element and an anvil, a driving mechanism, means comprising a link and coupling member normally tending to connect said work engaging element to said driving means, a stationary plate connected to the driving mechanism and having a cam formed therein, and means on the coupling member to cooperate with

130

the cam to hold the coupling member from engagement with the driving mechanism, whereby to prevent a coupling of the driving mechanism and work-engaging element until 5 the latter reaches a predetermined point in its working stroke.

3. In a safety device, in combination with a movable work engaging element provided with a stud shaft and an anvil, a driving 10 mechanism, means comprising a link and coupling member normally tending to connect said work engaging element to said driving means, said coupling member being carried by and pivotally seated on said link, 15 a stationary plate connected to the driving mechanism and having a cam formed therein and its free end bifurcated to fit the stud shaft, and means on the coupling member to coöperate with the cam, said cam being 20 formed so that said coupling member is prevented from exerting a pressure upon the work engaging element until it reaches a predetermined point in its working stroke.

4. A safety attachment for machines 25 equipped with a reciprocating work-engaging element, a driver and an anvil, and means to actuate said element from the driver comprising a link, a coupling member on the link and a stationary cam plate

30 to move said coupling member from engagement with the driver, said coupling member being movable transversely of the axis of the driver to and from a position of direct coupling engagement with the driver.

35 5. In combination with a work engaging element, an anvil and a driving mechanism having a crank pin, a link slidably attached to said crank pin, a coupling member co-operative directly with the crank pin and

40 pivotally attached to said link, and means to actuate the coupling member to automatically and rigidly couple the link to the crank pin so as to cause the work engaging element to exert pressure upon the

45 anvil at a predetermined point in its working stroke.

6. In combination with a work engaging element carrying a stud shaft and a bushing, an anvil and a driving mechanism having a 50 crank pin, a link slidably attached to said crank pin, a coupling member directly co-operative with the crank pin and pivotally attached to said link, and stationary cam means to actuate the coupling member to

55 automatically and rigidly hold the link in uncoupled relation to the crank pin so as to cause the work engaging element to avoid pressure upon the anvil if the element encounters an object extraneous to the work

60 before it reaches a predetermined point in its working stroke.

7. In combination with a work engaging element and driving mechanism embodying a crank, means to automatically couple said 65 driving mechanism and work engaging ele-

ment comprising a rigid link and a coupling member, said coupling member being pivoted on the link and movable transversely of the axis of the crank to and from a position of direct coupling engagement with the 70 crank, and means to prevent said coupling member and link from operating the work engaging element when an object extraneous to the work is engaged by the element while the latter is upon its working stroke. 75

8. In combination with a work engaging element and a driving mechanism embodying a crank, means to couple said driving mechanism and work engaging element comprising a rigid link and a coupling member, 80 said coupling member being pivoted on the link and movable transversely of the axis of the crank to and from a position of direct coupling engagement with the crank, and means to prevent said coupling member from engaging the driving mechanism when an obstruction extraneous to the work is in the path of the element and to permit said coupling member to engage the driving mechanism whereby to exert a pressure 85 upon the work engaging element when the path of the element is free.

9. In combination with a work engaging element and a driving mechanism embodying a crank, means comprising a movable 90 rigid link and a coupling member to couple said driving means and work engaging element to subject the work engaging element to a pressure when it reaches a predetermined point in its working stroke, said 100 coupling member being pivoted on the link and movable transversely of the axis of the crank to and from a position of direct coupling engagement with the crank, and means to prevent coupling of the member 105 and driving mechanism so as to prevent the work engaging member from being subjected to pressure upon encountering an obstruction extraneous to the work before it reaches said predetermined pressure point. 110

10. In combination with a work engaging element and driving mechanism, means comprising a yieldingly mounted rigid link and a coupling member to couple said driving means and work engaging element to subject 115 the work engaging element to pressure when it reaches a predetermined point in its working stroke, and stationary cam means to coöperate with the coupling member and prevent coupling of the member and driving 120 mechanism to prevent the work engaging member from being subjected to pressure upon encountering an obstruction extraneous to the work before it reaches said predetermined pressure point, a stud shaft and 125 bushing carried by the work engaging element; said stationary cam means having its free end bifurcated to engage the bushing.

11. In combination with a work engaging element, driving mechanism therefor, and a 130

stationary element to receive and resist pressure from the work engaging element, a link having a slot provided in one end through which said driving mechanism freely travels 5 independently of the link, a coupling member pivotally mounted on the link for coupling said link to the driving mechanism, by direct coupling engagement with the latter, means for exerting pressure through the coupling member upon the work engaging element at a predetermined point in its working stroke when the path of the work engaging element is free, and means to actuate the coupling member to coupling position when 10 the path of the element is free.

12. In combination with a work engaging element and driving mechanism; means to connect said driving means and element

comprising a rigid link and a coupling member, said coupling member being pivotally mounted on the link and movable to and from a coupling position of direct coupling engagement with the driving mechanism, and means to actuate the coupling member into engagement with the driving mechanism whereby to render the link operative to exert pressure upon the element when its path is free and to render the link inoperative when the element encounters an obstruction in its path extraneous to the work. 20 25 30

In testimony whereof I affix my signature in presence of two witnesses.
